Primary Examiner — Prabhakar Deshmukh*(74) Attorney, Agent, or Firm* — Reilly Intellectual Property Law Firm(57) **CLAIM**

The ornamental design for a latch extender, as shown and described.

DESCRIPTION

FIG. 1 is a front perspective view of a latch extender showing my new design;

FIG. 2 is a rear perspective view;

FIG. 3 is a top view of FIG. 1;

FIG. 4 is a left side view of FIG. 1;

FIG. 5 is a front view of FIG. 1;

FIG. 6 is a right side view of FIG. 1;

FIG. 7 is rear view of FIG. 5; and,

FIG. 8 is a bottom view of FIG. 1.

The broken lines in the drawings are intended to show the contours of the surfaces of the claimed design.
